(57) **CLAIM**

The ornamental design for a bottle support for endoscope flushing pump as shown and described.

DESCRIPTION

1.1 is a front isometric view of a bottle support for an endoscope flushing pump in a first configuration;

1.2 is a rear isometric view thereof;

1.3 is a front view thereof;

1.4 is a rear view thereof;

1.5 is a side view thereof;

1.6 is an opposite side view thereof;

1.7 is a top view thereof;

1.8 is a bottom view thereof;

1.9 is a front isometric view of the bottle support for an endoscope flushing pump in a second configuration;

1.10 is a rear isometric view thereof;

1.11 is a front view thereof;

1.12 is a rear view thereof;

1.13 is a side view thereof;

1.14 is an opposite side view thereof;

1.15 is a top view thereof; and

1.16 is a bottom view thereof.

(Continued)

In the drawings, the broken lines are for the purpose of illustrating portions of the bottle support for endoscope flushing pump that form no part of the claimed design.

1 Claim, 16 Drawing Sheets
